UNITED STATES PATENT OFFICE.

CHARLES W. HAMEL, OF ST. LOUIS, MISSOURI.

GAME APPARATUS.

1,411,723.

Specification of Letters Patent. Patented Apr. 4, 1922.

Application filed October 28, 1920. Serial No. 420,099.

To all whom it may concern:

Be it known that I, CHARLES W. HAMEL, a citizen of the United States, residing at St. Louis, Missouri, have invented a certain 5 new and useful Improvement in Game Apparatus, of which the following is a full, clear, and exact description, such as will enable others skilled in the art to which it appertains to make and use the same, reference being had to the accompanying drawings, forming part of this specification.

My invention has relation to improvements in game apparatus and is more particularly adapted to a baseball game, although such games as golf, cricket, football, and other field games can be played with the same apparatus, suitable modifications being made in the notations to correspond with plays arising in the particular game.

20 The present application is more particularly an improvement on my copending application for game apparatus, filed May 22, 1919, Serial Number 298,957, this application embodying an improved play indicating device and an improved play recording board.

The object of the present invention is to provide a play indicating device whereby practically every play that is likely to arise 30 in a contest may be simulated by means of my invention.

A further object is to provide a play recording board whereon the results of plays may be recorded with facility and whereon 35 the order of the players participating may be easily kept track of.

A further object is to provide a play recording board whereon suitable objects are utilized to represent the players and their 40 respective positions, means being provided for maintaining the objects in their proper positions and relative sequence.

Other and further objects will be better apparent from a detailed description of the 45 invention in connection with the accompanying drawings, in which—

Figure 1 represents the play indicating device superposed in position on the play recording board.

50 Figure 2 is a plan view of the play recording board detached, some of the objects located in positions denoting results of the play.

Figure 3 is a horizontal cross sectional 55 detail on line 3—3 of Figure 2, the objects remaining in elevation.

Referring to the drawings, 1 presents a frame provided with a transverse shaft 2 on which are mounted the play indicating devices 3, 3, said devices consisting of a suitable housing 4, provided with vertical partitions 5, which partitions divide the housings into a series of seven compartments each, designated by the numeral 6. Each of the housings 4 is provided with a transverse opening 7 on each of its four sides, said transverse openings extending across all of the compartments 6 and being covered with a transparent wall to permit of the play objects 8 being viewed from outside. 70 The construction of the play indicating devices is substantially the same as that of my copending application above referred to, in that the transparent walls are shaped so as to form a series of pockets each of which 75 coincides with a corresponding opening in the peripheral wall of the housing 4. Each compartment contains a number of objects marked to indicate different plays. These objects can be of any size or form such as 80 balls, and the openings in housing 4 are of proper size so that only one of such objects can enter the transparent pocket when in lowermost position through said opening. As the housing is rotated, the object is carried upwardly in said pocket a sufficient 85 distance to bring it into the full view of the player. The objects which do not enter the various pockets of each compartment roll downwardly onto the bottom of the 90 compartment. During the next operation of the housing or housings, the objects which have been carried upwardly in the pockets are discharged from said pockets, while 95 different objects are brought into view in the succeeding pockets.

Each of the compartments 6 represents a play possible in the game and the objects contained within a compartment are variously colored which permits of reference 100 to another compartment identified by the same color whereby a play or a series of plays may be followed to their conclusion. This will be clear from the following example:

To start play, we will rotate by means of the knob 9 the righthand housing 4, thus causing the objects 8 to tumble in their respective compartments and come to rest within sight when the housing is brought 110 to rest. The first compartment designated "1" discloses the plays on the batter and

if a white object comes to rest in this compartment, a "strike" is denoted on the batter, and if a black object comes to rest here, then a "ball" is denoted on the batter. If 5 some other colored object comes to rest in this compartment, for instance, an orange colored object, then for further particulars we are referred to compartment 2, designated "orange", which compartment represents a "safe hit to the outfield." If the 10 object coming to rest in compartment 2 is of the same color as one of the bases represented on the diamond of the play recording board (to be hereinafter referred to) then 15 the safe hit was via that particular base or in its vicinity. In this manner, by following the particular color from compartment to compartment and reading the inscription in spaces 10 below each compartment, we 20 are enabled to follow the play to its conclusion, it being understood, of course, that when different colored objects appear, then different plays are indicated.

It is also possible by means of this play 25 indicating device to call a play, that is, if a runner is on first base and it is desired to indicate his intention to steal second, the player will call a "steal" and thereupon the lefthand housing is rotated and by referring to compartment 11, and the inscription beneath said compartment, the result 30 of the play is determined; for instance, if a red object appears in compartment 11 the runner is out and if a brown object appears 35 then the steal was successful and the runner is safe.

It will thus be apparent that when a baseball game is being played, reference to the compartments denoted by the color of the 40 objects will enable my improved device to indicate practically every play that ordinarily comes up in a ball game. So too, if the game is golf, the inscriptions below the compartments and above the same will be 45 changed to correspond with plays that will come up in the game of golf.

The primary feature involved in my invention is the use of a series of compartments and differently marked objects, said 50 objects having reference to one or more of the compartments, the compartment being indicated by the color of the object.

In Figure 2 I have illustrated the play recording board which consists of a bottom board 11, the righthand side of said bottom board having marked thereon a baseball diamond 12 in this particular instance (in another instance a golf course may here be marked), the respective players being represented on the diamond by differently colored 60 objects and the bases being represented by differently colored objects so that a particular color in the play indicating device will refer one to the same color on the play recording device, and thereby designate the 65

base or the player where a particular play took place. On the lefthand side of the play recording board 11 are a series of grooves, these grooves being adapted to receive the differently colored objects 13 which 70 represent the players in the game. Referring to these grooves more particularly, groove 14 is dove-tail in cross section and is adapted to receive objects 15, said objects upon being inserted in the groove not being 75 removable except by removing a plate 16 fitting into recesses 17 at the open end of the groove. The object of thus holding the objects 15 in place is to prevent confusion in 80 the batting order of the players, since each 85 one of these objects is colored to represent the corresponding player of the diamond 12, and thus representing particular players, these players on any given team having fixed batting orders. If, however, a different team 90 is represented, then, of course, the objects 15 will have to be rearranged to represent players of that particular team. There are two 95 of these sets of objects 15 in their respective grooves 14, one representing the "ins" 100 or those who are at bat, and the other representing the "outs" or those who are in the field and are so designated on the board.

Contiguous to the objects 15 which denote the batting order of the players are objects 13, above referred to, these latter objects being freely removable from their grooves 18 for it is with these objects 13 that the result of plays is denoted. For instance, a groove 19 is provided to receive those players which have been "put out" in the play, while a groove 20 in line with groove 19 is to receive those players who have been successful in scoring runs, there being sufficient space in groove 20 to record five 105 runs. On the lower righthand side of the board 11 a groove 21 is provided which is marked off so as to provide space for the object representing the batter and is further provided with spaces marked off to denote 110 a player or players who have been successful in reaching a particular base or bases.

It is thus seen that in my improved recording board I have provided means for denoting the batting order of players which 115 may be permanent for any one game and which cannot be accidentally disarranged. I have also provided means for recording the result of plays and means for recording "runs" or points that have been scored in 120 the course of the play. In addition to this, the diamond or field whereon the plays occur is so marked that it is possible to account for the manner in which the play was made.

It will be understood that my improved play recording board need not necessarily be used in conjunction with my play indicating device, as any device used for indicating plays could have these recorded on 130

my recording board. Furthermore, while the present description necessarily refers to a baseball game, I do not wish to be understood as limiting myself to the same, nor do

5 I wish to be understood as limiting myself to the identical recording board shown in the drawings, but I wish to avail myself of the many modifications to which the present invention is susceptible.

10 Having described my invention, I claim:

1. In combination with a game apparatus, a play recording board, interchangeable members arranged on said board and provided with individual marks for indicating 15 players in their proper sequence, and objects for indicating the results of plays, said objects being referable to said members for indicating players by having individual marks which coincide with the 20 marks on said members.

2. In combination with a game apparatus, a play recording board having an undercut groove, distinctively marked objects interchangeably arranged in said groove for 25 indicating the order of the players, and correspondingly marked objects removably arranged on said board for recording the result of plays.

3. In combination with a game apparatus, a play recording board, said board being provided with interchangeable distinctively marked objects, manually operable means for temporarily holding said objects against displacement, and correspondingly 35 marked objects movably arranged on said board for indicating the result of plays.

4. In a game apparatus, a play recording board, a series of marked objects interchangeably held in position on said board 40 to indicate the sequential arrangement of the players, a series of player indicating objects marked to correspond with the first mentioned objects and removably held in position on said board, means on said board 45 for temporarily receiving said player indicating objects to indicate the playing posi-

tions of the players, and means for temporarily receiving said player indicating objects to indicate the results of the play.

5. In a game apparatus, a play recording 50 board, a series of marked objects interchangeably held on said board, means for locking said objects in position, a series of player indicating objects marked to correspond to the first-mentioned objects, means 55 on said board for removably receiving said player indicating objects in the order indicated by the first-mentioned objects, means for temporarily receiving said player indicating objects to indicate the playing 60 positions, and means for temporarily receiving said player indicating objects to indicate the results of the play.

6. In a game apparatus, a play recording board provided with a groove adapted 65 to removably receive a series of position indicating objects, means for retaining the objects in said groove in positions indicated by the first mentioned objects, a second groove adapted to temporarily receive a 70 series of objects, and auxiliary grooves for receiving the last mentioned objects.

7. In a game apparatus, a play recording board provided with a dove-tail groove, a series of distinctively marked objects 75 removably positioned in said groove, and manually operable means for preventing the displacement of said objects.

8. In a game apparatus, a play recording board provided with a dove-tail groove having an open end, a series of distinctively marked objects slidably positioned in said groove, means for closing the open end of said groove, thereby preventing the displacement of said objects, a second groove 85 adapted to receive a series of objects marked to correspond with the first-mentioned objects, and auxiliary grooves for temporarily receiving said last-mentioned objects.

In testimony whereof, I hereunto affix 90 my signature this 25th day of October, 1920.

CHARLES W. HAMEL.
